Primary Examiner — Eric Goodman*Assistant Examiner* — Amy Wierenga(74) *Attorney, Agent, or Firm* — Shook, Hardy & Bacon L.L.P.(57) **CLAIM**

The ornamental design for a garment, as shown and described.

DESCRIPTION

FIG. 1 is a front view of a garment in an as-worn configuration according to the present design;

FIG. 2 is a back view thereof;

FIG. 3 is a bottom-up view thereof;

FIG. 4 is a front view of the garment in a laid-flat configuration according to the present design; and,

FIG. 5 is a back view thereof.

The evenly spaced broken lines shown in the drawings are directed to environment, are for informational purposes only, and form no part of the claimed design.

The long and short broken lines are boundary lines, which define the bounds of the claimed design. These boundaries do not exist in reality in the article embodying the design. It is understood that the claimed design extends to these boundaries but does not include the boundaries.

The surface shading on the claimed portion is provided only to indicate the character and/or any contour or curvatures of the surfaces.
